Attorneys

UNITED STATES PATENT OFFICE.

CHARLES R. SEABORNE, OF APPLETON, WISCONSIN, ASSIGNOR TO AMERICAN LAKES PAPER COMPANY, OF CHICAGO, ILLINOIS, A CORPORATION OF DELAWARE.

ENGRAVING METHOD AND APPARATUS.

Application filed October 6, 1924. Serial No. 742,081.

My invention has reference more particularly to a method of and apparatus for marking or engraving the surfaces of large rolls, such as are used in the manufacture of paper to produce patterns or designs on the paper in the manner which is commonly called "water marking."

The rolls which are used for water marking paper are very large, and it has been extremely difficult and expensive, on account of their size, to provide the necessary configuration or design on the surfaces of the rolls. With my invention however, a simple device is employed whereby the marking or engraving of patterns or designs on large rolls of this character is accomplished easily and at a comparatively small expense.

The principal objects of my invention are to provide a simple and convenient method and apparatus for engraving or marking designs or patterns on the surfaces of large rolls; to minimize the expense of marking or engraving designs on large rolls of the character used for water marking paper; to construct the device so that it is capable of operating on rolls of different sizes; to arrange the device so that it is shiftable to different operating positions whereby successive sections of the surface of the roll may be marked or engraved; to utilize a small inexpensive master pattern; and in general, to simplify, improve and reduce the cost of engraving or marking the surfaces of large rolls such as are used in paper making and make it possible for the engraving or marking to be readily performed without requiring a high degree of skill on the part of the operator.

On the drawings:

- Fig. 1 is an end view of a device embodying my invention;

Fig. 2 a top view thereof, with portions of the supporting parts at one end omitted;

Fig. 3 an enlarged sectional view on the line 3-3 of Fig. 2;

Fig. 4 an enlarged sectional view on the line 4-4 of Fig. 2;

Fig. 5 an enlarged sectional view on the line 5-5 of Fig. 2;

Fig. 6 a similar sectional view on the line 6-6 of Fig. 2;

Fig. 7 a top view of a multiple engraving head; and

Fig. 8 a sectional view thereof, on the line 8-8 of Fig. 7.

Referring to the drawings, the base of the machine comprises a pair of end sills 10 which are spaced apart a suitable distance to accommodate therebetween the length of the roll 11 which is to be marked, said sills being held in the spaced relation in any convenient manner as for example, by connecting same with cross braces or by securing the sills 10 directly to the floor. Each of the sills 10 has a bracket 13 thereon with bearings 14 for anti-friction rolls 15 which engage the projecting ends of the shaft 16 of the roll 11, so that the roll 11 may be readily turned.

Brackets 17 and 18 extend upwardly at the front and rear ends respectively of the sills 10, and the brackets 17 of the two sills are connected together at their upper ends by the angle iron 19, while the brackets 18 of the two sills 10 have their upper ends connected together by an angle iron 20. A long guide plate 21 is secured to the upper or horizontal flange of the angle iron 20 and extends from side to side of the machine, and has the edges projecting beyond the upper flange of the angle iron as shown in Fig. 3, so as to be engaged by guide flanges 22 of the base 23 of an eidograph. This base 23 is slidable lengthwise of the plate 21, and may be locked in any position of adjustment thereon by the thumb screw 24 which engages a threaded aperture in the base 23 and clamps against the plate 21.

The two arms 25 of the eidograph are pivoted on the base 23 at 26, so as to swing in a horizontal plane, and have their outer ends pivoted at 27 to an intermediate plate 28 which is located over the guide plate 21, and this intermediate plate 28 preferably has an anti-friction roller 29 at each end riding on the upper surface of the guide plate 21. Each of the arms 25 is also provided over the base 23 with an anti-friction roller 30, which operates on a raised track 100 formation 31 on the upper face of the base 23.

The eidograph also has another pair of arms 32 which are pivoted at 33 to the intermediate plate 28 and extend substantially at right angles to the arms 25 over the roll 11, and the outer ends of these arms are pivoted at 34 to the head 35, which latter has

an extension 36 in the form of a bent arm provided with an operating handle 37 at the outer end.

An elongated guide plate 38 is mounted 5 on the upper or horizontal flange of the angle iron 19 as indicated in Fig. 6, and supports a pattern holder 39, which is formed with flanges 40 engaging respectively the front and rear edges of the plate 10 38, so as to be movable therealong. A thumb screw 41 is threaded through the front guide flange 40 for locking the pattern holder 39 in various positions of adjustment along the plate 38. This pattern holder 39 is preferably 15 formed with a shallow seat in the upper face to receive a pattern 42, which latter has on its upper face the design which is to be engraved on the roll 11, said pattern being held in place by cap screws 43 20 at each end, which engage through apertures in the ends of the pattern 42, and are threaded into the pattern holder 39. Recesses 44 are preferably provided in the pattern for the heads of the cap screws. For leveling 25 up the pattern 42, a screw 45 is threaded through same adjacent each corner so as to bear against the bottom of the seat in the pattern holder 39.

The outer end of the bent arm 36 is provided 30 with a tracer stylus 46 which is located so that it may be operated by means of the handle 37 to follow the design of the pattern 42, when the latter is adjusted to the proper position along the plate 38, and 35 the head 35 has a routing or engraving tool 47 mounted thereon, which by reason of the eidograph structure which carries both the engraving tool and tracer stylus, is caused to follow a path corresponding to that of 40 the tracer stylus 46 and serves to engrave the design of the pattern 42 on the surface of the roll 11 as the tracer stylus 46 follows the design of the pattern 42.

The routing tool 47 is mounted to rotate 45 in a barrel 48 and driven from any suitable source of power through the flexible shaft 49, or in any other convenient manner, and the head 35 is formed with a hub 50, having an aperture to receive the barrel 48 50 which is clamped in position in any convenient manner, as for example, by the set screw 51.

It will be observed that the routing tool 47, in order to properly engrave the surface 55 of the roll 11, is required to follow a curved line of elevation as it moves across the crown of the roll 11, and to this end the upper surface of the pattern 42 is curved from front to rear as shown particularly in Fig. 6 on 60 a radius which bears the same relation to the radius of the roll 11 as the distance of the routing tool 47 from the centers 33 bears to the distance of the tracer stylus 46 from the same centers. The radius of the upper 65 surface of the pattern 42 is therefore, suffi-

ciently less than the radius of the roll 11, so that as the stylus 46 at the outer end of the bent arm 36 moves forwardly and backwardly over the surface of the pattern 42, the routing tool 47 remains constantly in 70 the same relative position with respect to the surface of the roll 11, so that when the routing tool is set for a certain distance of penetration, it will cut a uniform depth at any point of adjustment, so long as the stylus 46 maintains the same relative position or depth of penetration in the upper surface of the pattern 42.

In engraving the cylinder the operator applies pressure to the handle 37 to hold 80 the tracer stylus 46 in engagement with the pattern 42. To lift the tool from engagement with the cylinder when pressure on the handle 37 is relieved a spring device is associated with the tracer. To this end a hub 52 is formed at the juncture of the handle 37 and bent arm 36 with an aperture in which the stem 53 is slidably mounted and the stylus 46 is secured by a set screw 54 or in any convenient manner in a socket 90 which is provided therefor in the lower end of the stem 53. The aperture in which the stem 53 is located is enlarged at the lower end as at 55 and contains a spring 56 which is compressed between the shoulder 57 at the upper end of the enlargement 55 and an annular flange 58 of the stem 53. Lock nuts 59 are threaded on the upper end of the stem 53 to hold the spring 56 under compression and limit the sliding movement 95 of the stem 53.

In the operation of this device, the pattern 42, which is of small area compared to the entire surface of the roll 11, bears a design which is to be marked on the surface of the roll 11. The eidograph is adjusted along the plate 21 and the pattern support 39 along the plate 28 and both locked in position, so that the operation of the device will transfer the pattern or design of the pattern 42 100 to a section of the surface of the roll 11 adjacent the end thereof. The design of the pattern is then marked on the section of the roll as indicated at 60 in Fig. 2, after which the roll 11 is turned the required extent so that the pattern may again be marked on the roll 11 in a section adjoining the previously marked section, and so that the design will 105 match up with the design which has been previously marked thereon.

To facilitate the turning of the roll for this purpose, a worm gear 61 is provided, which may be secured to the projecting end of the shaft 16 so as to mesh with a worm 110 62 on a shaft 63, carried by bearings 64 and 65 of the brackets 18 and 17 respectively. The bearing 65 is preferably formed with a dial on the face thereof, and the shaft 63 is provided with a pointer 66 for convenience in adjusting the roll, and the shaft 63 115 120 125 130

has a hand wheel 67 on the forward end for adjusting same.

By turning the roll 11 the proper amount after each transfer of the design of the pattern 42, a complete band of the design is marked around the roll 11. After this band is completed, the eidograph and pattern are adjusted respectively along the plates 21 and 38, so as to mark a series of sections adjacent to and matching with the designs forming the band around the end of the roll, and another band is thus marked on the roll and successive bands marked thereon until marking of the entire surface of the roll has been completed.

If desired, the head 35 may be constructed so as to simultaneously transfer the design of the pattern onto a plurality of adjoining sections of the surface of the roll by forming the head as shown at 68 in Figs. 7 and 8, with a plurality of laterally spaced routing tools. One of these tools 69 is mounted in an aperture of the boss 70 by means of the set screw 71, while the other routing tool 72 is mounted in an aperture of a block 73 which is adjustable on the head 68. The head has a rectangular opening 74 to receive the block 73, which is held therein by oppositely extending flanges 75 on the lower end and a plate 76 which is secured to the upper end. This block is adjustable to and from the routing tool 69 by the adjusting screws 77, so that the routing tools may be properly arranged so that the design made by one routing tool will match up with the design marked on the roll by the other routing tool.

From the foregoing it will be observed that I have provided a simple and convenient device by means of which the surfaces of large rolls may be readily engraved with a design, at a comparatively small cost, and that the device is capable of being readily operated without necessitating a high degree of skill on the part of the operator.

While I have shown and described my invention in a preferred form, I am aware that various changes and modifications may be made without departing from the principles of my invention, the scope of which is to be determined by the appended claims.

I claim as my invention:

1. In an apparatus for engraving a design on the cylindrical surface of a marking roll, a main frame having supporting means for the roll, a pantographic engraving device having a suitable supporting base, a tool and a tracer, a pattern corresponding to a relatively small segment of the cylindrical surface of the roll and adapted to cooperate with said tracer to guide the tool of the pantographic device to limited extents longitudinally and circumferentially of the roll to engrave a corresponding segmental section of its surface, and means for holding

the roll and said supporting base and pattern against movement during the engraving operations, said means permitting relative, axial and circumferential adjustments of the roll and said base and pattern to bring different longitudinal and circumferential segmental sections of the roll surface into the field of operation of the tool.

2. In an apparatus for engraving a design on the cylindrical surface of a roll, a main frame having means for rotatably supporting the roll, a pantograph frame, a supporting base therefor, an engraving tool and a tracer mounted on said pantograph frame, and a pattern corresponding to a relatively small segment of the cylindrical surface of the roll and adapted to cooperate with said tracer to guide the tool to limited extents longitudinally and circumferentially of the roll to engrave a corresponding segmental section of its surface, said supporting base and said pattern being longitudinally adjustable on said main frame to different fixed positions and said roll being rotatably adjustable to different fixed positions, whereby different longitudinal and circumferential segmental sections of the roll surface are brought into the field of operation of said tool.

3. In an apparatus for marking a design on the surface of a roll, a support for the roll, a pattern, an eidograph, said pattern and said eidograph being longitudinally adjustable relative to the roll into a plurality of fixed operative positions whereby the same pattern may be used to mark successive longitudinal portions of the roll and means for turning said roll about its axis to present successive circumferential portions of the roll to the eidograph and for holding the same stationary during the marking operations.

4. An apparatus for marking a design on the surface of a roll, comprising a support for the roll, an eidograph, said eidograph being mounted so as to be longitudinally adjustable relative to the roll into a plurality of fixed operative positions, a pattern mount and a support therefor, said mount being adjustable on the support into a plurality of fixed operative positions corresponding to the various fixed operative positions of said eidograph.

5. In an apparatus for engraving a design on the surface of a marking roll, the combination of a main frame having means for rotatably supporting the roll and having supporting guides extending longitudinally of the roll, a pantographic engraving device, a cooperating pattern corresponding to a relatively small segmental section of the surface of the roll, supports for said engraving device and said pattern mounted on said guides respectively and adjustable longitudinally thereof to a plurality of fixed

- positions, and means for rotatably adjusting said roll and for holding the same against movement during the engraving operations.
6. In an apparatus for marking a design on the surface of a roll, the combination of a support on which the roll is mounted to turn, an eidograph extending transversely over the roll and having a base adjustable lengthwise of the roll, a marking tool and a tracer stylus carried by said eidograph and a pattern adjustable lengthwise of the roll and having a curved surface, the radius of which is in the same proportion to the radius of the roll as the distance between the marking tool and the base of the eidograph is to the distance between the tracer stylus and the base of the eidograph.
7. In an apparatus for engraving a design on the surface of a marking roll, the combination of a main frame having means for rotatably supporting the roll, a pantograph frame having a base mounted on said main frame and adjustable lengthwise of the roll, a tool and a tracer carried by said pantograph frame and a pattern mounted on the main frame and adjustable lengthwise of the roll, said pattern corresponding to a relatively small segmental section of the cylindrical surface of the roll and having a segmental cylindrical surface upon which the design is marked, said pattern cooperating with the tracer to guide the tool to limited extents longitudinally and circumferentially of the roll and maintain the depth of its cut uniform.
8. An engraving machine comprising a supporting frame provided with bearings for sustaining the roll to be engraved, a pattern support mounted at one side of the longitudinal axis of said roll, a pattern mounted on said support and adjustable thereon in the direction of the axis of the roll into a plurality of fixed positions upon said support, a tool support extending longitudinally of said roll and upon the side of its axis opposite the pattern support, a tool carrier adjustable lengthwise upon said tool support, a routing tool and holder therefor supported by said tool carrier and located between said pattern support and said tool support, an arm connected to the holder of the routing tool and provided with a tracing stylus, said stylus being mounted over said pattern, and gear mechanism for rotating said roll in its bearings to bring different parts of its surface opposite said routing tool.
9. The method of engraving a design upon the cylindrical surface of a marking roll that consists in preparing a pattern corresponding in area to a relatively small segmental section of the area of the cylindrical surface of the roll, mounting said pattern for adjustment longitudinally of the roll to different fixed positions, mounting a pantographic engraving device for adjustment to correspond to the different positions of adjustment of the pattern, mounting the roll for rotatable adjustment to bring different circumferential segmental sections thereof into cooperative relation with the pantographic device and pattern, effecting such adjustments, and, while the roll is held stationary, employing the pattern in each of said different adjustments to guide the engraving device to engrave a corresponding segmental section of the surface of the roll.
10. An engraving machine comprising a supporting frame provided with bearings for sustaining the roll to be engraved, a pattern support mounted at one side of the longitudinal axis of said roll, a pattern mounted adjustably in the direction of the axis of the roll upon said support, a tool support extending longitudinally of said roll and upon the side of its axis opposite the pattern support, a tool carrier adjustable lengthwise upon said tool support, a routing tool and holder therefor supported by said tool carrier and located between said pattern support and said tool support, an arm connected to the holder of the routing tool and provided with a tracing stylus, said stylus being mounted over said pattern, and gear mechanism for rotating said roll in its bearings to bring different parts of its surface opposite said routing tool.

C. R. SEABORNE.
